W. E. EVERITT.

APPARATUS TO HOLD AND BEND SPRINGS.

APPLICATION FILED FEB. 8, 1919.

1,323,971.

Patented Dec. 2, 1919.

UNITED STATES PATENT OFFICE.

WALTER EDWARD EVERITT, OF SEATTLE, WASHINGTON.

APPARATUS TO HOLD AND BEND SPRINGS.

1,323,971.

Specification of Letters Patent.

Patented Dec. 2, 1919.

Application filed February 8, 1919. Serial No. 275,878.

To all whom it may concern:

Be it known that I, WALTER EDWARD EVERITT, a citizen of the United States, residing at Seattle, in the county of King and State of Washington, have invented certain new and useful Improvements in Apparatus to Hold and Bend Springs; and I do hereby declare the following to be a full, clear, and exact description of the invention, such as will enable others skilled in the art to which it appertains to make and use the same.

This invention relates to apparatus for bending spring leaves and particularly to bending spring leaves of the type used in vehicular construction.

It is the object of the present invention to provide an apparatus of this type which is simple, practicable, easily operated, and by which spring leaves of various proportions and sizes may readily be bent to the desired form and it is an important object of the present invention to provide for the differential curvature of one of the leaf springs with relation to another so that the maximum efficiency of the leaves can be utilized when they are assembled into the leaf or bolster organization.

Another object of the invention is to provide means for varying the pressure of the forming or pressure roll and holding it permanently at the desired pressure during the operation.

Another object of the invention is to provide for the use of the machine with spring leaves of different types as for instance, those having apertures in their centers or those merely having punch marks.

With these and other objects in view which will readily be made manifest to those versed in the art, the invention consists of the construction, the combination, and in details and arrangements of the parts as more particularly described in the following specification relative to the embodiment of the invention illustrated in the accompanying drawings, in which,

Figure 1 is a side elevation of the machine showing the master leaf and the spring leaf to be bent thereto in position.

Fig. 2 is a perspective view of the device with one of the supporting arms broken away, and illustrating a plurality of the

leaves in the clamping roll, the leaves being in cross section.

Fig. 3 is a detailed sectional view of the upper portion of the apparatus.

Figs. 4 and 5 are side elevational views of the throat plate for the bracket arms.

Fig. 6 is a detailed view of the clamp for embracing adjacent ends of the leaves which are shown in section.

Fig. 7 is a plan view of the structure shown in Fig. 6.

Fig. 8 shows the reversible jack pin upon which the leaf or leaves are supported.

The machine comprises generally a substantial post or column 1 with suitable reinforcing brackets or base members 2. Straddling this post is a bifurcated swinging lever member 3, the side ends of which are slotted at the lower ends at 4 to pass over a pivot pin 5, removably mounted in the lower portion of the post 1. The upper end of the swinging lever 3 is provided with a handle 8 by which it may be manipulated to and fro from the upper end of the post. Just below the handle 8, there is a rocker shaft 9 having a pawl or click 10 designed to swing down into engagement with the toothed upper edge of a lever 11 which is pivoted at 12 on the upper end of the swinging arm 3. The rock shaft 9 is provided with an operating lever 13 by which the pawl 10 can be disengaged from the toothed upper edge of the lever 11, which lever has a downwardly extending portion 14 through which is passed a pin 15, upon which is mounted a pair of links 16, connected by a pin 17 to the upper end of a slide 18, arranged between the side arms of the lever 3. The pins 15 and 17 are of sufficient length to form seats for the ends of a spring 19 which surrounds the links 16 the lower ends of which are slotted as clearly shown in Fig. 3 at 16' so as to provide for the compression of the spring 19 by means of the lever 11.

Within the slide 18 there is mounted a pressure roller 20 designed to engage and operate upon a spring 21 when it is applied to a master spring 22 or other form the ends of which are suitably supported upon bracket arms 23 and 24, which are laterally adjustable with respect to the post or

column 1. These arms are provided with curved portions 25 to be passed through a respective seat portion therefor 26, Fig. 3, and may be securely locked or temporarily 5 clamped into proper adjusted position by means of wedge-keys 27, attached by chains 28 to the post to prevent their being misplaced. One of the wedge-keys 27 is provided with a pin 29 designed to be passed through an aperture 23 in one of the side 10 arms of the lever 3 and to engage a complementary aperture in the post so as to lock the arm 3 in vertical position.

The upwardly extending arm of the 15 bracket 24 is provided with a cross-head 31 having an upwardly extending threaded portion 32 on which there is pivotally mounted a wedge-shaped hub or locking cam 33 having a lever 34 extending from 20 the side thereof and by which the cam 33 can be turned so that its thin portion as shown in Fig. 6 can be brought over the upper end of the cross head or seat 31 to permit the insertion of the spring leaf and 25 master forms 21 and 22, after which the lever 34 can be swung so as to turn the thick portion of the locking end 33 into binding engagement upon the inserted ends of the 30 spring leaf and form. The opposite edges of the leaf and form are supported by means of a swiveled stop or rest 35 shown as in the shape of a U-shaped piece which may be pivoted upon the lateral extension 36 of the cross head 31 to provide for adaptation of 35 the clamping device to leaves of various width. The upper end of the bracket 23 is provided with a pin or rest 40 upon which is pivotally mounted side stop 41 through one 40 end of which and the opposite end 42 of the arm 23 there may be passed a locking key or fastener 43 which is connected by a chain 44 to the arm 23 to prevent loss of the key. The side stop 41 is laterally adjustable on the seat or rod 40 in a manner similar to 45 the member 35 shown in Fig. 6, to provide for adaptation of the rests or supports to springs of different widths.

Some times leaf springs are provided at 50 their central portions with apertures to receive a centering device and again they are provided only with punched seats and in order to adapt the present device to operate upon either form of spring leaves there is shown in Fig. 8 a reversible jack pin 45 with 55 a rather elongated point 46 for use with springs which have only punched seats and the opposite end of the jack pin 45 is provided with a short tapered point 47 for use with spring leaves which are apertured. 60 One of the important features of the present invention is to provide an apparatus whereby the curvature of the master spring may be varied so as to give differential curvature to the different leaves of a pile and to that 65 end the present apparatus includes an ad-

justable supporting member upon which the jack pin 45 may be arranged. This is shown clearly as comprising in Fig. 3 a lever 48, one arm 49 of which is provided with a seat to receive the pin 45, the upper 70 end of which is guided in a bracket or guide portion 50 having an aperture at the upper portion and a slot in the side arm through which the adjacent end 49 of the lever 48 swings. The guide 50 is mounted upon the upper end of the stationary column or post 1 and on the side thereof there is provided a bracket 51 having a pivot 52 upon which the lever arm 48 is mounted. The outer 75 arm of the lever 48 is provided with a series 80 of apertures 53 in any of which may be mounted a pivot pin 54 in the upper end of a connecting rod 55 the lower end of which is pivotally connected at 56 to foot pedal 57 pivoted at 58 to one side of the post 1. The 85 pedal 57 and the lever 53 normally rock upward so as to hold the seat 49 in lowermost position by any suitable means, here shown as comprising a spring 59 connecting the lever 57 to the main post or column 1. 90

For the purpose of preventing the swinging-arm 3 from teetering or swaying after it passes the post or column 1, the latter is provided on each side with a suitable form of support or guide 60. 95

In operation of the device the clamp 33 on the bracket arm or support 24 is opened, as is also the locking pin 43 on the bracket 23 and the master leaf or former 22 inserted beneath the roller 20 which is held in an elevated position by means of a spring 61 connected to the lever 11, then the spring leaf 21 to be formed or shaped is placed upon the master leaf 22 and one end of it is clamped by the wedge member 33, the leaves 21 and 22 being centered with respect to each other by the upper end of the jack pin 45 and the master leaf is supported upon co-axial rollers 62 provided therefore between the side arms of the lever 3. Then the lever 11 is lowered so that the pressure roller 20 is brought into contact with the upper leaf 21 and the lever 3 is swung toward the clamp 33 and the spring 19 is compressed to the suitable pressure by pulling down the lever 11 which may be locked in the desired position by the pawl 10 which keeps the spring 19 compressed and the roller 20 held against the upper leaf 21. The arm 3 is then swung away from the clamp 33 by means of the operator grasping the handle 8 and this movement bends the upper spring 21 to the master 22, the free end of the spring leaf 21 being forced down toward the rod or support 40 after which it may be keyed or locked into position by the pin 43. The lever 3 is then manipulated a sufficient number of times to shape or form the leaf 21, approximately to the master 22, after which in order to give a differential curve to the 110 115 120 125 130

two members the operator presses down the 5 pedal 57 so as to lift the lever seat 49 and carry the jack pin 45 upward increasing the deflection of the master 22 and also the leaf 10 spring 21 superposed thereon after which the operator swings the lever 3 to and fro to press the spring to the desired form. Therefore when the operator has released pressure 15 on the pedal 57, the jack pin 45 is forced down by the resiliency of the master spring 22 after which the leaf spring 21 may be released from the clamp and holders and it will be found to have been given a curvature different from that found in the master 22.

What I claim is:

1. In an apparatus of the character set forth in the specification, a supporting bracket having an up-standing arm with a 20 cross piece forming a seat, and a wedge-like disk for clamping superposed elements to the seat, and an adjustable side rest, for the elements, opposite to the clamp.

2. In an apparatus for shaping leaves of 25 laminated springs, means for centering the leaf and a master; means for holding the superposed elements during the process of shaping, and a shaping means comprising a lever having a slide carrying a presser roll, 30 the lever shiftable from end to end of the elements, means on the lever for holding the roll with desired pressure against the work comprising a pivoted lever carried by said first mentioned lever and pivotally connected 35 to a link having a slotted end, a pin secured to said slide and engaging the slotted end of said link, and a compression spring intermediate said pivoted lever and said pin.

3. In an apparatus for shaping leaves of 40 laminated springs, means for centering the leaf and a master; means for holding the superposed elements during the process of shaping, and a shaping means comprising a lever having a slide carrying a presser roll, 45 the lever shiftable from end to end of the elements, means on the lever for holding the roll with desired pressure against the work comprising a pivoted lever carried by said first mentioned lever and pivotally connected 50 to a link having a slotted end, a pin secured to said slide and engaging the slotted end of said link, a compression spring intermediate said pivoted lever and said pin and 55 means for locking said pivoted lever.

4. In an apparatus for shaping leaves of 55 laminated springs, means for centering the leaf and a master; means for holding the superposed elements during the process of 60 shaping, and a shaping means comprising a lever having a slide carrying a presser roll, the lever shiftable from end to end of the elements, means on the lever for holding the roll with desired pressure against the work, 65 comprising a pivoted lever carried by said

first mentioned lever and having a downwardly extending portion, a link having a slotted end, a pin connecting said link and downwardly extending portion, a pin connecting said slide and said link, one of said pins 70 engaging the slot in said link and a spring intermediate said pins.

5. In an apparatus for shaping leaves of 75 laminated springs, means for centering the leaf and a master; means for holding the superposed elements during the process of shaping, and a shaping means comprising a lever having a slide carrying a presser roll, and lever shiftable from end to end of the elements, means on the lever for holding the 80 roll with desired pressure against the work comprising a pivoted lever carried by said first mentioned lever and having a downwardly extending portion, a link having a slotted end, a pin connecting said link and 85 downwardly extending portion, a pin connecting said slide and said link, one of said pins engaging the slot in said link, a compression spring intermediate said pins, and means for locking said pivoted lever comprising a pawl on said first mentioned lever engaging a rack on said pivoted lever.

6. In an apparatus for shaping leaves of 90 laminated springs, a support, means for centering the leaf and a master carried by said support; means for holding the superposed elements during the process of shaping, also carried by said support and a shaping means comprising a lever pivoted to said support 95 and having a slide carrying a presser roll, 100 the lever shiftable from end to end of the elements, and self-locking means for holding the roll with desired pressure against the work, the last named means comprising a pivoted lever a spring intermediate said lever and slide, and a latch for said pivoted lever.

7. In an apparatus for shaping leaves of 105 laminated springs, a support, means for centering the leaf and a master carried by said support; means for holding the superposed elements during the process of shaping, also carried by said support, and a shaping 110 means comprising a lever adjustably pivoted to said support and having a slide carrying a presser roll, the lever shiftable from end to end of the elements, a guide for said lever carried by said support and self-locking means for holding the roll with desired pressure against the work, the last named means 115 comprising a pivoted lever, a spring intermediate said lever and slide and a latch for said pivoted lever.

8. In an apparatus for shaping leaves of 120 laminated springs; a support, means for 125 holding the superposed elements carried by said support, shaping means movable longitudinally of the supported elements, and means for centering the superposed elements and varying the curvature of the master 130

leaf or templet to differentiate the leaves of a set from each other at any time during the operation of shaping the leaves, comprising a lever pivoted intermediate its ends to said support, a depression in one end of said lever, a pin slidably supported by said frame and having its lower end engaging the de-

pression in said lever, a spring supported treadle and a rod having one end pivotally secured to said treadle and the other adjustably connected to the other end of said lever. 10
In testimony whereof I affix my signature.

WALTER EDWARD EVERITT.
